UNITED STATES PATENT OFFICE.

DELMAR A. WHITSON, OF LOS ANGELES, CALIFORNIA, ASSIGNOR, BY MESNE ASSIGNMENTS, TO STENTORPHONE COMPANY, OF LOS ANGELES, CALIFORNIA, A CORPORATION OF CALIFORNIA.

LOUD SPEAKER.

Application filed August 30, 1922. Serial No. 585,159.

To all whom it may concern:

Be it known that I, DELMAR A. WHITSON, a citizen of the United States, residing at Los Angeles, in the county of Los Angeles and State of California, have invented a new and useful Improvement in Loud Speakers, of which the following is a specification.

My invention relates to the art of telephony and relates particularly to a telephone receiver which may be employed to deliver a magnified volume of sound. Receivers of this character are commonly called loud speakers and have their particular application in the art of radio telephony in which they are employed with receiving sets for the purpose of making the sounds transmitted by radio audible to persons situated at a distance from the device, thus making it possible for a large number of persons to hear broadcasted material received by a single set.

It is an object of the invention to provide a loud speaker which may be constructed and distributed at a low first cost owing to the simplicity of the construction thereof.

It is a further object of the invention to provide a device of this character which will deliver sound amplifications which may be heard throughout an ordinary sized room or which may be adjusted to modulate the sounds delivered thereby by varying the strength of the exciting circuit.

It is an object of the invention to provide in this simplified form of device a diaphragm having connection with a magnetic vibrating means consisting of an armature in which magnetic fluxes are maintained in constant balanced relationship when not influenced by the exciting magnetism, so that residual magnetism is not built up within the armature.

It is a further object of the invention to provide a simplified form of construction in which the operating elements of the device are mounted upon the underside of a cover plate and are removable therewith from the shell, and are therefore easy of access for adjustment.

The specific advantages of the invention and further objects thereof will be made evident hereinafter.

Referring to the drawing which is for illustrative purposes only,

Fig. 1 is an elevational view, drawn to

a small scale, showing a loud speaker of my invention having the amplified horn thereof in place ready for use.

In Fig. 2 is an enlarged vertical sectional view through the loud speaker shown in Fig. 1 but with the amplifying horn removed therefrom.

Fig. 3 is a section taken on a plane represented by the line 3-3 of Fig. 2.

Fig. 4 is a schematic diagram illustrating the principles involved in my invention.

As shown in the drawing I provide a shell 11 mounted upon a base 12 and having a cover member 14 which fits into the top thereof. The shell 11 is cylindrical and the cover member 14 is also of cylindrical formation, thus adapting it to facility in performing machine operations. The member 14 is provided with an upwardly extending central projection 15 provided with an opening 16 adapted to receive the lower end 18 of an amplifying horn 19. In the underside of the cover 14 a shallow stepped circular recess 20 is formed, having central communication with the opening 16. Across the recess a diaphragm 25 is secured by a ring member 26 which attaches to the underside of the cover member 14 by means of screws 28.

Upon the underside of the ring member 26 I mount a small U shaped magnet 30, this magnet being provided with downwardly extending poles 31 and 32. Beneath the magnet 30 and preferably in the same vertical plane therewith, as shown, a permanent magnet 35 is placed with the poles 36 and 37 upwardly directed, the pole 36 being shouldered as indicated at 38, and attachment thereof made with the pole 31 of the magnet 30 by means of a screw 40. The pole 37 of the magnet 35 is supported by a brace 39 which is attached also to the ring 26. The poles 32 and 37 are beveled off as indicated at 42 and a gap is provided therebetween through which an armature 45 extends. This armature 45 is flexibly secured to the end of the pole piece 31 by means of a screw 47 and has an exciting coil 48 mounted therearound, this coil being situated between the poles of the magnets, as shown in Fig. 2, and having a central tube 49 through which the armature 45 extends.

The free end 48 of the armature 45 is connected by a link member 49 with the center 50 of the diaphragm 25.

As indicated in Fig. 4 the magnets 30 and 35 are so magnetized and placed that the north pole of each magnet is adjacent to the south pole of the other magnet, thus creating a magnet structure in which a free circuitous flow of magnetic flux may pass. The course provided for the flow of magnetic flux is continuous except for the interposition of the gap 55. The exciting coil 48 surrounds the body of the armature 45 and is energized through leads 57 and 58 which are connected with a suitable receiving set.

It will be perceived that whenever a current is flowing through the coil 40 a magnetic flux will be impressed in the armature 45, this flux having a polarity depending upon the direction of flow of the exciting current. It will be seen that if the direction of current is such that the forward end 48 of the armature is given positive polarity, the armature will be repelled by the north pole of the magnet 35 and attracted by the south pole of the magnet 30, thereby producing a combined action of forces upon the armature to cause its upward movement and the upward movement of the diaphragm 25 by virtue of the connection therewith of the link 49 which connects between the diaphragm and the end 48 of the armature, movable in the plane of the magnets.

An essential feature of my invention resides in the manner in which the magnetic field provided by the magnets 30 and 35 is short-circuited by the armature 45 so that a flow of magnetic fluxes takes place as indicated by the arrows 60 and 61. These counter-flowing fluxes preserve a balanced state of magnetism in the armature which opposes the collection of residual magnetism therein due to the activating magnetic flux created by the energization of the exciting coil 48, and further assists in clearing whatever slight amount of residual magnetism may take place in the armature due to the energization of the coil 48. In this manner I am able to provide a very simple equipment which is susceptible to rapid vibrations and which, being free of residual magnetic influences, delivers a faithful sound reproduction.

It will be perceived that in the construction of the shell and the cover, it is possible to remove the entire mechanism from the shell by simply lifting the cover therefrom, thus making it a very simple matter to make any necessary adjustment.

I claim as my invention:

1. In a loud speaker, the combination of: a pair of depending magnets placed in substantially the same vertical plane and with the positive pole of each magnet adjacent to the negative pole of the other magnet, a positive pole of one of said magnets being directly in contact with a negative pole of

the other of said magnets; an armature having one end secured to one of said magnets and the other end thereof extending between the negative pole of one of said magnets and the positive pole of the other of said magnets; an exciting coil surrounding said armature for creating a flow of magnetic flux therein having a density corresponding to the strength of current flowing through said coil; a diaphragm; a shell surrounding said magnets; link means for imparting the movement of said armature to said diaphragm; and means for supporting said diaphragm horizontally at the top of said shell.

2. In a loud speaker, the combination of: a pair of vertically aligned magnets placed with the positive pole of each magnet adjacent to the negative pole of the other magnet, a positive pole of one of said magnets being directly in contact with a negative pole of the other of said magnets; an armature having one end thereof between a negative pole of one of said magnets and a positive pole of the other of said magnets; an exciting coil surrounding said armature for creating a flow of magnetic flux therein having a density corresponding to the strength of current flowing through said coil; a shell surrounding said magnets and provided with a cover; a diaphragm; link means between said diaphragm and said armature for imparting the movement of said armature to said diaphragm; and means for supporting both said diaphragm and said magnets from said cover.

3. In a loud speaker, the combination of: a magnet structure providing a circuitous flow of magnetic flux, said structure having a gap therein; an armature having one end thereof situated in said gap in said magnet structure and having the other end thereof in engagement with said magnetic structure a point opposite to said gap; an exciting coil surrounding said armature for creating a flow of magnetic flux therein having a density corresponding to the strength of current flowing through said coil; a diaphragm; a shell surrounding said magnets and provided with a cover; link means for imparting the movement of said armature to said diaphragm; and means comprising a ring for supporting both said diaphragm and said magnets from said cover.

4. In a loud speaker, the combination of: a shell; a substantially vertical magnet structure suspended within said shell and providing a circuitous flow of magnetic flux, said structure having a gap therein; an armature having one end thereof situated in said gap in said magnet structure and having the other end thereof in engagement with said magnetic structure a point opposite to said gap; an exciting coil surrounding said armature for creating a flow of magnetic flux therein having a density corresponding to

the strength of current flowing through said coil; a diaphragm supported within the upper part of said shell; and link means between said diaphragm and said end of said armature for imparting the movement of said armature to said diaphragm.

5. In a loud speaker, the combination of: a pair of magnets placed with the positive pole of each magnet adjacent to the negative pole of the other magnet, a positive pole of one magnet being attached to the negative pole of the other magnet, and a gap being provided between the other negative pole and the other positive pole; an armature 10 having one end thereof disposed in said gap and the other end thereof flexibly supported at the joining point of said magnets and against an end of one of said magnets; an exciting coil surrounding said armature for creating a flow of magnetic flux therein having a density corresponding to the strength of current flowing through said coil; a diaphragm; and link means for imparting the movement of said armature to said diaphragm.

6. In a loud speaker, the combination of: a pair of magnets placed with the positive pole of each magnet adjacent to the negative pole of the other magnet, a positive pole of one magnet being attached to the negative pole of the other magnet, and a gap being provided between the other negative pole and the other positive pole; an armature having one end thereof disposed in said gap and the other end thereof flexibly supported at the joining point of said magnets; an exciting coil surrounding said armature for creating a flow of magnetic flux therein having a density corresponding to the strength

of current flowing through said coil; a diaphragm; a shell; a cover to which said magnets are secured by means comprising a ring, and link means between said diaphragm and said end of said armature for imparting the movement of said armature to said diaphragm.

7. In a loud speaker, the combination of: a shell; a removable cover for said shell, said cover having an annular recess formed upon the under side thereof and an opening 50 through said cover situated substantially centrally of said recess; a diaphragm across said recess; a ring member securable upon the underside of said cover for holding said diaphragm across said recess; a U-shaped 55 magnet secured upon the underside of said ring member, with the poles thereof extended downwardly; a U-shaped magnet mounted upon said ring member beneath said first named magnet, and with the poles thereof 60 directed upwardly, the negative pole of one of said magnets being secured to the positive pole of the other of said magnets, there being a gap between the other said positive and negative poles of said magnets; an armature flexibly attached to said first magnet at the point at which said magnets are joined, and extending horizontally through said gap; an exciting coil for creating a flow of magnetic flux in said armature; and a 65 link extending between the movable end of said armature and the center of said diaphragm for transferring the movement of said armature to said diaphragm.

In testimony whereof, I have hereunto set my hand at Los Angeles, California, this 16th day of August 1922.

DELMAR A. WHITSON.
